UNITED STATES PATENT OFFICE.

WILLIAM N. ROWE, OF HIBBING, MINNESOTA.

SECTION-CARRIER FOR STEAM-SHOVELS.

1,374,527.

Specification of Letters Patent. Patented Apr. 12, 1921.

Application filed March 8, 1920. Serial No. 364,027.

To all whom it may concern:

Be it known that I, WILLIAM N. ROWE, a citizen of the United States, residing at Hibbing, in the county of St. Louis and 5 State of Minnesota, have invented certain new and useful Improvements in Section-Carriers, for Steam-Shovels, of which the following is a specification.

This invention relates to section carriers 10 for steam shovels.

It is customary in the operation of steam shovels, that when the shovel has excavated as much as it can in front, to lay a short section of track, usually about six feet long, 15 in front of the steam shovel so that the latter can move forward. The short section which is swung around the front of the shovel is the one which the steam shovel has traveled off of last at the rear. The 20 picking up of this section and carrying same forward and placing in the proper position, involves arduous labor. To pull the spikes, remove the rails, and carry the ties forward singly, lay them down and re- 25 construct the section, involves much labor. In my improved device the section in the rear of the steam shovel is picked up bodily and intact and placed in position for advancing the steam shovel in a manner greatly 30 reducing the labor and time involved in the operation.

One object of the invention is to transfer a section of track bodily from one position to another with respect to a steam 35 shovel in a simple, novel and efficient manner whereby arduous labor is eliminated and time and money are saved.

Another object is to provide a simple and safe trolley arrangement which is adapted 40 to prevent the trolley from being derailed.

Another object is to provide a collapsible trolley track arrangement whereby the steam shovel equipment may occupy the minimum amount of space, useful particularly in moving the steam shovel from one 45 location to another.

These and other objects are accomplished by means of the arrangement disclosed on the accompanying sheets of drawings, in 50 which—

Figure 1 is a side elevation of a steam shovel equipped with my section carrier;

Fig. 2 is a top plan view of the same; Fig. 3 is an end elevation of the same arrangement;

Fig. 4 is a detail view showing the connecting means between the main part of the trolley track and a pivotally mounted section thereof forming part of a jib crane; and,

Fig. 5 is a top plan view of the arrangement shown in Fig. 4.

The various novel features of my invention will be apparent from the following description and drawings and will be particularly pointed out in the appended claims.

Referring to the figures of the drawings, it will be noted that I have illustrated my invention in connection with a steam shovel equipment which may be designated generally by the reference character 10. The steam shovel equipment, among other things, includes a car frame 11 mounted on trucks 12 and having the usual housing 13 in which is mounted the engine and other necessary machinery for actuating the dipper, not shown, carried at the end of the dipper support 14.

This invention has to do primarily with means for transferring a section of track, 80 including two rails and the ties which connect same from one end of the shovel to the other in order that the shovel may approach more closely a bank of material to be dug,

especially after the dipper has been extended the maximum amount for removing the material in the bank. To accomplish the desired results, I have mounted lengthwise of the shovel at either side thereof, trolley tracks 15, the tracks in this case 90 extending from end to end of the shovel and being connected at their rear ends by a transversely arranged track 16.

The front portion of each of the tracks 15 normally registers with a track section 17, 95 which is in the form of an arm of a jib crane at the front of the shovel, the arm or section 17 in each case being fixed to a vertically arranged supporting member 18, which in turn is suitably supported on the 100 shovel.

When it is desired to transfer a track section from one end of the shovel to the other, for example, from the rear end to the front,

end, for the reasons stated, a rigging 19 is secured to the track section in any suitable manner, the rigging being connected to a chain 20, which is operatively connected to 5 a block 21 carried by a trolley 22, the wheels 23 of which travel upon the lower flange of the trolley rail 15 on either side of the web thereof. It will be assumed that the trolley is located at the rear of the shovel 10 some place along the trolley track 16, and that the track section to be transferred has been raised a certain predetermined distance through the operation of the chain 20. To convey the track section 24 from the rear of 15 the shovel to the front thereof, I have provided a small engine 25 mounted upon the trolley track section or arm 17 and which in this case might be a fluid propelled motor. This motor includes a drum having connected thereto a cable 26, which is connected 20 to the trolley 22, so that when the drum is actuated to wind the cable thereon, the trolley 22, and therefore the track section when secured to the trolley, is transferred 25 forwardly from the rear end of the shovel.

To prevent the trolley 22 from dropping to the ground from the track 15, it is necessary that the track section or swingably mounted arm 17 be in register with the 30 track 15 at the time that the trolley 22 moves forwardly from the latter. To make the connection between track 15 and the associated arm 17 secure and safe, I have provided connecting means therebetween, 35 shown particularly in Figs. 4 and 5. This connecting means includes a slidably mounted member 27 mounted over the top flange of the rail 15, the forward end of which passes between upstanding projections 40 28 carried on the upper flange of the rail section 17. Therefore, when it is desired to transfer the trolley from track 15 to track section 17, the slidably mounted member 27 is in locking relationship with respect to 45 its associated locking members 28. Secured to the track 15 is a support 15' which extends under the free end of arm 17 for supporting the latter when it is in alinement with track 15. In order that the trolley 50 may be transferred from track 15 to track section 17, it is first necessary to move a locking bolt 29 out of the path of movement of the trolley wheels. This is done by drawing downwardly upon a cable 30 connected 55 to a bell crank lever 31, which in turn is pivotally connected at 32 to a bracket 33.

After the trolley has been transferred safely from track 15 to track section 17, as shown in Figs. 4 and 5 of the drawings, the locking bolt 29 may be dropped to form a safety device to prevent the trolley 22 from accidentally rolling off the track section 17, especially during a swinging movement of the latter. Preferably the lock bolt 29 is

of such weight that it automatically moves 65 into its locking position when the cable 30 is released. In order that the track section 17 may be swung away from the track 15, it is necessary to withdraw the sliding member 27 from its associated locking projections 28. This is done by drawing downwardly upon a cable 34 secured to a bell crank lever 35 pivoted at 36 to a bracket 37, one arm of the bell crank being slotted to 70 slidably accommodate a pin or projection 38 carried by the sliding member 27. Preferably the sliding member 27 is normally held in its locking position and when withdrawn automatically returned to such position by any suitable means, such as a spring 75 38'. I do not limit myself to this mechanical arrangement to accomplish this end, as obviously other details of construction could be designed. When the trolley is safely on the swingably mounted track section or arm 80 17, as shown in Figs. 4 and 5 of the drawings, the track section may be swung about the member 18 as a vertical axis, as indicated by dotted lines in Fig. 2, until the track section is placed in a position to align 85 with the track sections upon which the shovel is mounted. It is necessary that the arms 17 be of sufficient length to swing the track section clear of the jacks 39, which, as is understood, are necessary to support 90 the shovel through arms 40 to prevent the shovel from tipping over. By referring to Figs. 2 and 3, and particularly the latter, it will be appreciated that it is necessary to 95 swing the track section 24 outwardly a considerable distance to clear the jack mechanism 39. By the arrangement here shown such is done in a simple and satisfactory manner.

When the shovel is stationed at a given 105 location, the tracks 15 are retained in their offset position with respect to the housing 13, as shown in the figures of the drawing. However, when it is desired to move the shovel from one location to another, which 110 may be a considerable distance away, it is desirable for clearance purposes to have the rails 15 occupy less space. To accomplish this object I have provided a collapsible 115 mounting for the rails 15, including supporting bars 41, which normally space the tracks 15 from the side of the housing 13. These supporting members 41 are pivotally mounted at their inner ends at 42. Diagonally extending tie bars 43 assist to support the tracks 15. These tie rods 43 are pivotally connected at their upper ends. By means of this arrangement the tracks 15 may be moved toward the car sides as the members 41 swing inwardly with respect to the housing 13, as indicated in dotted lines in Fig. 2 of the drawings. Normally it will be understood, however,

that the tracks 15 are locked in their extended position by removable tie rods 44.

By means of this equipment, track sections may be moved from one end of the 5 shovel to the other in a simple, safe and economical manner and the extending parts of the equipment be moved into positions requiring a relatively small amount of space when it is desired so to do.

10 It is my intention to cover all modifications of the invention falling within the spirit and scope of the following claims.

I claim:

1 In steam shovel equipment, the combination of a trolley track extending from the front to the rear of a steam shovel for carrying a track section over which the shovel moves, and a jib crane on the front end of the shovel having an arm which in one position 20 registers with the trolley track and is sufficiently long to permit the carried track section to clear jack mechanism supporting the shovel and whereby said track section may be placed in proper position.

25 2. In steam shovel equipment, the combination of a trolley track extending along the side of the shovel for transferring a track section over which the shovel moves, and a jib crane on one end of the shovel 30 having an arm which in one position registers with the trolley track and is sufficiently long to move the track section clear of jack mechanism which supports the shovel and by means of which the track section may be 35 transferred to the proper position.

3. In steam shovel equipment, the combination of a trolley track extending along the side of the shovel for transferring a track section over which the shovel moves, 40 a jib crane on one end of the shovel having an arm which in one position registers with the trolley track and is sufficiently long to move the track section clear of jack mechanism which supports the shovel and by 45 means of which the track section may be transferred to the proper position, and means mounted on the jib crane for propelling a trolley along the track.

4. In steam shovel equipment, the combination of a trolley track for conveying a track section over which the shovel moves from one position to another, a jib crane having an arm for registering with said track whereby a trolley may pass from the 55 track to said arm, and safety means whereby the trolley cannot accidentally fall from said track or arm.

5. In steam shovel equipment, the combination of a trolley track for conveying a 60 track section over which the shovel moves from one position to another, a jib crane having an arm for registering with said track whereby a trolley may pass from the track to said arm, safety means whereby the

trolley cannot accidentally fall from said 65 track or arm, and means for locking said track and arm in coöperating position.

6. In steam shovel equipment, the combination of a trolley track for conveying a track section over which the shovel moves 70 from one position to another, a jib crane having an arm movable with respect to said trolley track, and means for automatically locking said trolley track and jib arm in a coöperative position whereby a trolley may 75 move from one to the other.

7. In steam shovel equipment, the combination of a trolley track for conveying a track section over which the shovel moves from one position to another, a jib crane 80 having an arm movable with respect to said trolley track, means for automatically locking said trolley track and jib arm in a coöperative position whereby a trolley may move from one to the other, and means for 85 automatically preventing the trolley from accidentally falling from said trolley track or jib arm.

8. In steam shovel equipment, the combination of a trolley track for conveying a 90 track section over which the shovel moves from one position to another, a jib crane having an arm movable with respect to said trolley track, means for automatically locking said trolley track and jib arm in a coöperative position whereby a trolley may 95 move from one to the other, means for automatically preventing the trolley from accidentally falling from said trolley track or jib arm, and means mounted on the jib arm 100 for drawing the trolley along said track.

9. In steam shovel equipment, relatively movable trolley tracks extending along the side of the shovel by means of which a track section over which the shovel moves may be 105 transferred from one end of the shovel to the other, and means for automatically locking said trolley tracks in a given relationship.

10. In steam shovel equipment, relatively 110 movable trolley tracks extending along the side of the shovel by means of which a track section over which the shovel moves may be transferred, means for automatically locking said trolley tracks in a given relationship, and means for automatically preventing a trolley from falling from said trolley track members.

11. In steam shovel equipment, relatively 115 movable trolley tracks extending along the side of the shovel by means of which a track section over which the shovel moves may be transferred, and means for automatically preventing a trolley from falling from said trolley tracks.

12. In a steam shovel equipment, the combination of a trolley track extending along 120 the side of the shovel for conveying a track

section over which the shovel moves, and means for supporting said trolley track whereby the same may be swung toward the shovel for clearance purposes.

5 13. In a steam shovel equipment, the combination of a trolley track extending along the side of the shovel for conveying a track section over which the shovel moves, and

pivotaly mounted supporting bars for said trolley track whereby the latter may be moved toward the shovel for clearance purposes.

Signed at Hibbing, Minnesota, this 20th day of February, 1920.

WILLIAM N. ROWE.
